HYDRAULIC POWER PRESS CONTROL

Harry P. L. Laussucq, Reading, and Bertrand Japikse, Reiffton, Pa., assignors to Birdsboro Steel Foundry and Machine Co., Birdsboro, Pa., a corporation of Pennsylvania

Application February 20, 1943, Serial No. 476,584

6 Claims. (Cl. 192—138)

1

This invention pertains to a hydraulic power press and more particularly to a stroke control device adapted to limit control or interrupt a downward action of a movable platen beyond a preset or predetermined degree.

An object of the invention is to provide, in a downward acting hydraulic press, cooperating means for rapidly and completely unloading the hydraulic system of the press at the time a movable platen thereof reaches a predetermined position in its downward movement so that a continued downward action of the platen is definitely arrested or interrupted.

A further object of the invention is the provision, in a hydraulic power press, of a dial arrangement having dual pointers, hands or independently movable means, one of which may be manually preset to determine or control definitely the limit of downward movement of a movable platen.

Still another object of the invention is to provide an electrical means carried by a dial arrangement and which may be affected upon dual pointers or hands of the arrangement becoming co-radial or coincident.

A more detailed object of the invention is the provision of a pressure stroke control in a hydraulic power press and having a fixed dial with a front manually movable arm arranged to be preset prior to the downward action of a movable platen and an additional or rear hand responsive to the downward action of a movable platen; both hands being so arranged and constructed that when they are co-radially disposed there is caused a release of the fluid pressure in the hydraulic power press system.

The above as well as numerous other objects of the invention will become apparent from the succeeding description taken into consideration with the accompanying drawings which disclose an exemplified form of the invention and wherein:

Figure 1 is a schematic or diagrammatic view of a hydraulic power press embodying the present invention.

Figure 2 is a front elevational view of a dial arrangement embodying a portion of the present invention arranged to cooperate with hereinafter described parts of the hydraulic power press illustrated in Figure 1.

Figure 3 is a vertical sectional view of the dial arrangement and taken along the lines 3—3 of Figure 2 looking in the direction of the arrows.

Figure 4 is a horizontal sectional view taken

2

along the lines 4—4 of Figure 2 looking in the direction of the arrows.

Figure 5 is a horizontal view shown partially in plan and partially in section and taken along the lines 5—5 of Figure 2 looking in the direction of the arrows.

Figure 6 is a vertical sectional view taken along the lines 6—6 of Figure 4 looking in the direction of the arrows.

10 Figure 7 is a vertical sectional view taken along the lines 7—7 of Figure 6 looking in the direction of the arrows.

15 Figure 8 is a vertical sectional view taken along the lines 8—8 of Figure 2 looking in the direction of the arrows.

Before reference is made to the drawings in detail, it may be stated generally that a press of the instant invention, during the first rapid operation of the press has a movable platen

20 thereof urged downwardly and before the movable platen contacts the work a bracket on the movable platen is arranged to contact a hardened washer and from that moment on a rear pointer or hand of the dial begins a clockwise movement around the dial. The action of the

25 movable platen will proceed until the platen stalls against the work. After the operator has satisfied himself that the work is properly clamped and has preset a front pointer or hand to a desired position, determined by measurement of

30 the amount of straightening that must be done, he will then move an operating lever beyond the fast approach position which will result at the same time in the tripping of a limit switch where-

35 by it becomes possible to build up operating tonnage. The movable platen will then proceed in a downward direction and the rear pointer will continue to travel around the dial until it reaches a position at which the front pointer or hand has

40 been preset. At this exact moment a sensitive electric switch is tripped by the dial mechanism and the electric circuit is broken to actuate a valve which is vented to release the pump delivery from the operating pump and at the same time releasing the hydraulic pressure in the system.

45 At this instant, therefore, it will be no longer possible for the movable platen to travel downwardly since its downward action or straightening operation is interrupted. The electric circuit in the press is so wired that building up pressure cannot be repeated until the operating lever has been actually pulled back causing the movable platen to be raised and thereby

50 making it impossible to build pressure which

would be harmful, not only to the work but to the operating mechanism of the press.

Referring now in detail to the drawings, wherein like reference characters indicate like parts, the numeral 1 is employed to designate in a general manner a hydraulic power press which exemplifies the present invention. Considering initially Figure 1 of the drawings, which, as previously stated, shows a somewhat diagrammatic view of the hydraulic power press, the press comprises a lower or stationary platen 2 having rising therefrom guide columns or posts 3 extending between and secured to a head 4 and the stationary platen. Arranged to move vertically of the press is an upper or movable platen 5 urged downwardly during the downward stroke of the press by a main cylinder 6 and raised upwardly during the return or reverse action or stroke of the press through the medium of pull-back cylinders 7. Forming the upper portion of the press is an overhead tank 8 which in the instant illustration functions as a combination surge tank and suction tank. Associated with the press and forming a part of the hydraulic system is a main pump 9 which supplies fluid pressure to the press and has a discharge line 10 running to a relief valve 11. When this relief valve 11 is closed the flow of fluid from the main pump takes place in the manner as indicated by the arrow into line 12, through the check valve 13 and then to the operating valve 14. The operating valve is a four-way type to permit the flow of fluid either to the main cylinder 6 from the port 15 thereof to cause a downward action of the movable platen or to the pull-back cylinders 7 from the port 16 and through the line 17 to cause an upward movement of the movable platen. When the operating valve is set to service the port 15 the opposite port or connection 16 is exhausted through the port 18, check valve 19, back pressure valve 20 into the line 21 and overhead tank 8. When on the other hand the operating valve is set to service the port 16 to thus operate the pull-back cylinders, the port 15 is exhausted through the port 18 into the overhead tank 8.

The relief valve 11 is of a commercial design or standard type and as such it is believed herein unnecessary to illustrate in detail. However, for a complete description of the operation of the press and particularly the hydraulic system thereof, it is deemed essential to state that the relief valve comprises a T-shaped body 11a having pressure connections 11b and 11c and a drain connection 11d through which the fluid pressure from line 10 will be by-passed when the relief valve is unloaded (as will be hereinafter described) into the back pressure valve 20, line 21 and overhead tank 8. More specifically, the relief valve has a seat in the bottom of the T portion and a relief valve plunger seats thereon. The upper part of the valve plunger fits snugly into a cylindrical portion of the relief valve body and through the use of a small auxiliary, spring loaded, supplementary relief valve built into the relief valve 11 variable pressures over the main plunger are automatically regulated to hold the plunger seated tightly until a predetermined blow-off pressure has been reached and then the valve will open up to proportional amounts to automatically allow it to open sufficiently to blow off the excessive fluid pressure delivered to the relief valve and at the same time maintain the full preset pressure in the hydraulic system. The nature of this relief valve is also such that if the pressure connection below the seat of the sup-

plementary relief valve were open to drain through port 11d, the relief valve 11 would be completely and immediately unloaded or vented in its entirety, thus completely negating or unloading the pump 9 and thereby releasing all pressure in the hydraulic system through the seat of the valve and through the bottom connection except that the valve is further equipped with a light spring which will always maintain a minimum pressure in the instant structure of approximately 65 pounds per square inch which is insufficient pressure to build up enough pressure in the press to do any work.

In the pipe line 22 running from port 15 of the operating valve to the main cylinder is placed a special valve part 23 which is in the nature of a combination relief valve 24 similar to the valve 11 and a flow regulating device which might be compared to a plug cock 25 with refinements for automatically adjusting the valve so that when once set up to permit a certain amount of fluid to by-pass through the valve to the main cylinder the amount of flow will remain constant irrespective of the pressure required to be built up in the main cylinder. The plug cock works in conjunction with the relief valve 24 in that the relief valve bleeds off through the discharge connection of the valve any excess fluid delivered by the pump above the amount which is metered through the plug cock portion of the valve. The fluid thus by-passed by the relief valve portion 24 returns through valve 20 back to the surge tank and is therefore wasted. In the diagram there is shown an outline for the valve body with a plug cock portion and a relief valve portion shown separately therein. This, however, is done for diagrammatic expediency. The special valve part 23 is also equipped with a small pilot or auxiliary relief valve same as in the valve 15 whereby the maximum pressure may be preset and the valve can again be vented and then the only pressure that can be developed in the system is equal to that created by the light spring (not shown) hereinbefore mentioned which gives approximately 65 pounds per square inch back pressure. This valve will permit full volume flow only in the forward direction and in order to permit the fluid to be exhausted from the main cylinder it is of course necessary to add a check valve 26 to by-pass the flow regulating and relief valve in the return flow direction.

It will be noted that from this valve 23 there is shown a vent connection which leads to three additional valves 27, 28 and 29. The purpose of valve 21 is to provide a means whereby pressure can be built up progressively and it comprises a small relief valve which is preloaded by a spring 30 which is initially set in the instant structure to give only about 65 pounds pressure per square inch or sufficient loading so that the spring will not actually slack but is mounted in such a manner that when an operating lever 31 is disposed at station A resulting in a closing action of the press or downward movement of the movable platen, the pressure of the spring against a ball 32 of the check valve is built up progressively as the lever is advanced further. Accordingly, the pilot relief valve 27 is preset to proportional blow-off pressures corresponding with the position of the operating lever and likewise the relief valve portion of valve 23 is loaded to higher pressure settings when the operating lever 31 is shifted away from center or to lower pressures when the lever is shifted closer to center. The positions 75 of the operating lever 31 indicate the following

operating conditions: When the operating lever is in position B the press platen is raised up at full speed; in position C the platen is stopped; in position A the platen is lowered rapidly to the work but no pressure can be built up on the work except the initial 65 pounds per square inch mentioned above. Between positions A and D pressure can be built up on the work but the amount of pressure that may be developed is proportional to the distance that the lever has been shifted between these two positions.

The maximum pressure that can be developed is in addition limited, however, by the relief valve 28 which is a micro-adjustable pilot relief valve and by adjusting the setting of this valve it can readily be seen that it is possible to limit the maximum value of pressure that can be developed by the use of the valve 27.

The hereinbefore described construction and arrangement has, it is believed, been previously employed. However, the introduction into the hydraulic system of the valve 29 marks a departure from the art and which deals with the advancement made over the prior art in that it is definitely associated with or functionally related to the dial control hereinafter described in detail. As will be noted, the valve 29 is connected to the vent system of the valve 23 and its two-way valve permitting flow of fluid to take place from port 33 to port 34 in which case the vent connection is open to the tank or this passage can be blocked by shifting the valve plunger. The connection to the port 35 in this valve is provided merely to remove slippage of fluid which may have escaped past the valve plunger clearances. This valve 29 is solenoid operated and so arranged that when the solenoid is deenergized the valve is open for flow from port 33 to port 34 and when the solenoid is energized the valve is closed. In view of the above, it will, therefore, be understood that when the solenoid is deenergized the entire pump delivery is being by-passed through the vented relief valve portion of valve 23 but as soon as the solenoid is energized the pump delivery is no longer by-passed but is then directed towards the main cylinder for the purpose of building pressure therein and this pressure can be built up to the value predetermined by the amount of loading on valve 27 but within the limitations made by the setting of valve 28.

A limit switch 36 is provided in the press for the purpose of energizing the solenoid of valve 28 and is so mounted that when the operating lever is moved the first initial distance beyond position A toward position D its circuit is closed thereby energizing the solenoid through relays (not shown). The valve 29, therefore, is closed at the moment that hydraulic pressure is being built up.

The hydraulic power press is provided with a dial control generally designated as at 37 which presents a control means whereby the circuit of the solenoid in the valve 29 can be broken instantly when the movable platen has traversed a predetermined distance. For this purpose the dial control mechanism will trip at that moment a micro-switch 38 (see Figures 3 and 4). The means by which this micro-switch is operated will be described hereinafter but for the present consideration it will be assumed that the movable platen has caused the switch to be tripped and the solenoid to be deenergized. The effect will be that the relief valve portion of the valve 23 will be instantly vented through ports 33 to port 34 in the valve 29, thereby disturbing completely

the balance of valve 23, the latter of which will then open instantaneously and by-pass the pump to exhaust the high pressure out of the hydraulic system of the press thus stopping or arresting the further downward travel of the movable platen. By making use of a device which unloads pressure by instantaneously unbalancing a valve plunger there is obtained a much faster action than if there were merely operated a piston type of valve by electric means because such a valve of the latter type generally has long laps which must be uncovered before the valve opens and of course, in such instances, some additional pressing work would be done while this uncovering of laps takes place, thereby materially increasing the amount of over travel which would be reflected in the press.

Referring now in detail to the dial control mechanism 37 illustrated in minute detail in Figures 2 through 8 inclusive, there is provided a supporting plate 39 angular in vertical cross section having a vertically disposed leg 39a which is secured to the stationary or lower platen by any desired means and a horizontal leg 39b forming a shelf for the support of the dial control mechanism. Mounted upon the supporting plate in fixed relation thereto is a control box 40 comprising a bottom plate 40a superimposed upon and secured to the horizontal leg by any desired means and joined top and side plates 40b and 40c respectively. Extending between the top, bottom and side plates and secured thereto preferably by means of welds are front or face and rear or back plates 40d and 40e respectively and which are vertically disposed and in horizontal spaced relation with respect to one another. Disposed within the control box desirably centrally thereof is a tubular element or ferrule 40f secured to the front and rear plates by means of welds to rigidify the box against stresses to which it will be subjected in service. The front and rear plates are provided with horizontally aligned circular apertures 40g in axial alignment with the ferrule for the accommodation of a hub 41 which has a head 41a outwardly of the front plate and secured firmly thereto and a shank 41b extending rearwardly from the head and arranged to fit neatly the aligned apertures 40g. Disposed within the hub and arranged to rotate therein is a main shaft 42 tubular in formation and thereby provided with an axial bore 42a extending entirely therethrough. Horizontally spaced bearings 42h are circumambient the main shaft and housed within the confines of the hub to maintain the main shaft in a predetermined or relatively fixed radial disposition.

Spaced forwardly of the control box is a washer-like disc or dial 43 preferably circular in formation having a central opening 43a and retained in position by means of quadrantly disposed brackets 44. Each bracket desirably comprises a foot 44a firmly secured to the control box front plate and having extending therefrom a stem 44b terminating in a re-entrant flange 44c welded or otherwise secured to the front face 43b of the dial to hold the latter rigid. Keyed to a shank 42b which forms a continuation of the main shaft and projects through the extended plane of the dial is a sleeve 45 arranged to respond to or move with the main shaft. Journaled to the sleeve and arranged to be moved manually relative thereto is a setting hand or outer or front pointer or marker 46 which has a bushing 46a thereof neatly fitting the sleeve and retained in journaled relation therewith by means

of a locking nut 41. Forming the main portion of the setting hand or marker is a setting hand bar 46b of rectangular formation and arranged to extend across the major portion of the stationary dial. The setting hand is provided with an adjusting hand 48 of substantially the same shape as the associated portion of the setting hand bar and has formed at one end thereof a hinge butt 48a which mates with a hinge butt 46c formed on the setting hand bar. A pin 46d extends through the half hinges or hinge butts and thereby provides a pivotal connection between the setting hand and adjusting hand. A housing 49 is formed on the adjusting hand to extend outwardly therefrom in a direction away from the setting hand and is provided with an opening 48a which is covered by a transparent pane 48b so that dust, dirt or any other foreign particles may be excluded from the mechanism encased in the housing which will be hereinafter described, as well as present a port through which the mechanism may be viewed for inspection purposes. The extremity removed from the hinge butt 48a of the adjusting hand is formed as a bifurcated lip 48b which accommodates a portion of a pin 48c to be pivotally connected thereto. A shank 49d of the pin extends through a suitable or aligned aperture in the setting hand to terminate in a finger 48e projecting inwardly of the dial control and into the plane of the stationary dial. As will be noted by referring particularly to Figure 2 of the drawings, the dial is provided with graduations or indicia means adjacent its periphery and in radial alignment with each graduation towards the center of the dial therefrom is an aperture 46e to present a series of equally spaced or circularly arranged apertures extending completely around the stationary dial. The apertures 46e accommodate the finger 48e so that the assembled setting hand bar and adjusting hand may be maintained in a predetermined position such, for example, as horizontal as illustrated in Figure 2 of the drawings and for the purpose to be hereinafter explained. Since the apertures beneath the setting hand are obstructed from view the adjacent extremity of the setting hand bar is pointed as at 46f so that an operator may align the pointed extremity with a particular graduation in the course of making his setting. The setting hand bar and adjusting hand are maintained in juxtaposition by means of a sleeve 50 secured to and outstanding from the adjusting hand and which houses a spring means such as the illustrated coil or helical spring 50a. The helical spring has its inner extremity bearing against the adjusting hand while its outer extremity reacts against a head 50b of a screw 50c, the latter of which extends through the spring and adjusting hand to be anchored in the setting hand bar. An operating handle 51 is provided on the adjusting hand so that the latter may be urged away from the setting hand bar about the pin 46d to withdraw the finger from a particular aperture during the process of rotating the setting hand; front pointer or marker to a different location or disposition. A similarly designed operating handle 51a is arranged to standout from adjacent the setting hand extremity removed from the pointed end so that in the course of making a setting both handles 51 and 51a may be employed.

Disposed inwardly of the stationary dial in parallel spaced relation thereto is an indicating hand or inner or rear pointer or marker 52 which is secured to and forms a part of the sleeve 45

so as to be also responsive to the rotary movement of the main shaft 42. The indicating hand has a tail portion 52a which acts as a counterbalance therefor and projects radially from the sleeve. 5 In radial alignment with the tail portion is a branch 52b which has a free extremity 52c of U-shaped formation extending about the outer edge of the stationary dial to terminate in a restricted portion or end 52d positioned in spaced 10 relation to the front face of the stationary dial as clearly indicated in Figures 2 and 3. The rear pointer is provided with a trip peg 53 which is positioned intermediate the sleeve and U-shaped extremity of the indicating hand and is threadedly 15 associated therewith so as to be adjustable transversely of the dial control. A jamb nut 53a is threadedly associated with a trip peg so as to retain the latter in a fixed position. The trip peg has a free extremity 53b thereof extending into 20 the projected plane of the stationary dial and into the central opening 43a so that the indicating hand may rotate unrestrictedly throughout its entire range of rotary movement. Equally spaced from the axis of the main shaft is an operating 25 pin 54 carried by a guiding nipple 54a which is secured to and forms an integral part of the setting hand bar. The guiding nipple extends through an opening 48f in the adjusting hand and into the housing 49 and has an inner end thereof restricted to form an abutment for a shoulder 54b on the operating pin and thereby 30 limit the movement of the latter in one direction. The extremity of the operating pin adjacent to the shoulder is rounded as at 54c and 35 lies in the circular path of the trip peg extremity 53b so that as the indicating hand moves in a clockwise direction as hereinafter explained and after an advanced presetting of the setting hand to a desired location, the trip peg extremity 53b will engage the operating pin extremity 54c and cause the operating pin to be shifted outwardly of the guiding nipple or displaced from normal 40 position.

Firmly secured to the setting hand bar and also 45 extending through the operating handle opening 48f into the housing at a location toward the main shaft from the guiding nipple is a trip lever clevis 55 which is pin-connected to a trip lever 55a intermediate the ends of the trip lever. One 50 extremity 55b of the trip lever is disposed in a suitable slot of the guiding nipple and bears against an associated extremity of the operating pin so that any outward movement of the operating pin will be reflected in the trip lever. The 55 trip lever from the clevis extends across an extended plane of the main shaft to have its opposite end 55c pivotally connected to a guide pin or plunger 55d which is held in a definite path by means of a cup 55e secured to and forming 60 a part of the setting hand bar to also extend into the housing through the adjusting hand opening. Associated with the main shaft is a switch operating rod 56 having a head 56a in abutting relation or intimate contact with the trip lever 55a and retained in such a position by means of a coil spring 56b encased by the main shaft and tending to urge the rod head outwardly therefrom. The switch operating rod 56 has a stem portion 56c which extends rearwardly from the 65 rod head through the main shaft bore 42a to be associated with the micro-switch 38 so that when the extremities of the trip peg and operating pin come in contact with one another the switch operating rod through the displacing action of the 70 trip lever will be urged through the main shaft 75

to trip the micro-switch, thus breaking the circuit in the solenoid valve 29 to result in the instant arrest of a continued downward movement of the movable platen.

Means has been provided to rotate the main shaft and indicating hand so that it may rotate from the zero or vertical position as indicated in Figure 2 in a clockwise direction until the trip peg contacts the advanced operating pin to trip the microswitch. For this purpose, therefore, there is provided a stroke control bracket 57 which is attached to and carried by the movable platen 5. The bracket is provided with a vertically disposed bushing lined orifice 57a arranged as a guiding medium for a vertical extension rod 58 which has a lower extremity fitting snugly into and firmly secured to an associated extremity of an operating rod 59. Surmounted upon the operating rod and circumambient the extension rod is a hardened washer 58a against which the bracket may strike upon a downward movement of the movable platen. As will be understood, the proper distance between the hardened washer and bracket is determined when the movable platen is at normal position and the indicating hand is at rest at zero or as shown in Figure 2. The operating rod is maintained in a predetermined path of travel by means of a guide bracket 59a rigidly secured to or mounted upon the control box top plate 40b. The operating rod is provided with a slot 59b extending transversely therethrough intermediate the ends thereof for the accommodation of a shoe 59c which is mounted on or secured to the control box back plate 40e. The shoe not only acts as a guide medium but also prevents the operating rod from rotating about its axis. The operating rod extends down to the area of the control box bottom plate where its lower extremity projects through, in sliding relationship thereto, an adjusting nut 59d which is threadedly associated with an adjusting nut bracket or leaf 59e secured to the bottom plate of the control box. A stop or locking pin 59f removably secured to the control box bottom plate has an extension 59g thereof which extends into a suitable orifice of the adjusting nut to retain the latter in a fixed position. Shims 59h are employed to position the locking pin so as to accommodate the particular vertical setting of the adjusting nut. A castle nut and hardened washer 59j are threadedly associated with the lowermost extremity of the operating rod to abut the adjacent portion of the adjusting nut. Mounted beneath the shelf 39b of the supporting plate is a limit switch 60 which has an arm 60a extending therefrom and positioned in the path of travel of the operating rod so that as the movable platen travels downwardly sufficiently to cause the bracket 57 to bear against the hardened washer 58a and urge the operating rod downwardly, the switch 60 will be tripped to prevent an overtravel of the movable platen under operating tonnage which, if not arrested, would cause damage to the dial and other parts of the press. This limit switch, therefore, operates relays (not shown) so that it too may cause solenoid 29 to become deenergized and thereby the movable platen can no longer be forced downwardly under hydraulic pressure. By a manipulation of the castle nut the operating rod may be adjusted to the exact position in order that its exact location may be set up on the press to obtain a predetermined travel at the desired elevation.

Removably secured to the back plate of the control box is a gear guard 61 which forms a shield for a train of gears 61a housed therein. Carried by the back plate of the control box is a stud 61b which has freely and rotatably associated therewith an operating sprocket 61c which extends partially into slot 59b of the operating rod. Draped over and in operable engagement with the operating sprocket is a roller chain 61d having one end thereof tangentially disposed relative to the sprocket and desirably common to the axis of the operating rod. A short distance below the referred to extremity of the roller chain is a bridge 61e formed in the slot of the operating rod and presenting an anchorage for a connection 61f which presents a means for tying the roller chain extremity to the operating rod. Accordingly, any downward movement of the operating rod will be reflected in the roller chain to cause a clockwise rotative movement of the operating sprocket. Disposed below the plane of the stud 61a is a similar stud 62 mounted on the rear plate of the control box and carrying a relatively rotatable compound sprocket 62a which comprises a chain sprocket 62b and a relatively larger gear 62c. The roller chain is intermeshed with teeth of the chain sprocket and wound partially therearound to have its adjacent free extremity firmly fastened to the chain sprocket. Accordingly, any rotative action of the operating sprocket in a clockwise direction will, through the roller chain, cause the compound sprocket to rotate about the stud 62 in a counter-clockwise direction. Keyed to the main shaft is a pinion 62d in intermeshing relationship with the gear 62c so that if the latter is rotated in a counter-clockwise direction the pinion will be rotated in a clockwise direction to result in the main shaft and indicating hand being rotated in a similar direction. A downward action of the movable platen will, therefore, toward the end of its downward movement, cause a rotative movement of the indicating hand and result in the trip peg contacting the operating pin for the above explained purpose.

Means has also been provided so that upon the completion of the straightening operation and the movable platen's return to raised or normal position, a reverse movement will be set up in the main shaft and related elements to also return the indicating hand to normal position. To accomplish the above, the main shaft in the rear of the pinion is provided with a sheave 63 which is keyed to the main shaft so as to move therewith. Mounted on a micro-switch support 63a below the plane and to the one side of the main shaft is a roller bracket 63b supporting a freely movable roller 63c. Supported by the bottom plate of the control box beneath the roller 63 is a shield 64 comprising a web plate 64a secured to the control box and having extending therefrom in opposite directions a tube 64b. Disposed within the tube and arranged to move relatively thereto is a top clevis 64c. Wound about the sheave and having one end firmly secured thereto is a cable 64d which trails over the roller and extends down into the tube to have its other end secured to the top clevis. The lower portion of the top clevis is provided with a cross pin 64e to which there is secured top extremities of coil or tension springs 64f. The lower extremity of the tube has, closing the clear opening thereinto, an apertured barrier 64g through which extends a bolt 64h depending from a bottom or lower clevis 64j. The bottom clevis is likewise provided

with a cross pin 64_k to which are anchored the lower extremities of the springs 64_f. An adjusting means or nut 64_m is threaded associated with the bolt 64_h so that a predetermined tension in the springs may be effected. Accordingly, any rotative movement of the main axle in a clockwise direction will result in the cable being further wound around the sheave and additional tension being built up in the springs connecting the clevises so that as the movable platen, upon completion of its downward stroke or movement, is started back to normal or raised position, the built up tension in the clevis springs will cause the counter-clockwise movement of the main shaft to return the dial control mechanism to normal position, as clearly indicated in Figure 2.

If after the hydraulic system has been actuated to return the movable platen to normal position it is determined that an insufficient amount of travel has been effected in the movable platen to straighten completely the work, the setting hand can be advanced around the dial to a new location with the distance advanced being determined by the amount of additional movable platen action required to straighten the work and then the operating cycle of the press can be initiated once more.

From the above it will be noted that various changes and alterations may be made to the herein described and illustrated construction without departing from within the spirit of the invention and the scope of the appended claims.

We claim:

1. In a pressure stroke control of a hydraulic power press, the combination of, a dial, a rotatable pointer arranged to be maintained fixed with respect to said dial, pivotal means carried by said rotatable pointer, a second pointer arranged to respond to a downward action of a movable platen of said press, means fixed relative to said second pointer and arranged to contact said pivotal means, means actuated by said pivotal means for limiting the downward action of said movable platen, and means connected to said second pointer for returning the latter to normal position.

2. In a hydraulic power press having a fluid operated movable platen, the combination of, a solenoid operated valve, a movable pointer arranged to be fixed at a predetermined position, a second pointer responsive to the downward action of a movable platen, pivotal means carried by one of said pointers, a fixed means carried by the other of said pointers, said pivotal and fixed means being adapted to contact one another upon said movable and second pointer reaching a predetermined relationship, and means actuated by said pivotal means for deenergizing said solenoid operating said valve and thereby causing an interruption in the downward action of said movable platen.

3. In a hydraulic power press having a fluid operated movable platen, the combination of, a solenoid operated valve, a dial, a movable pointer arranged to be fixed with respect to said dial at a predetermined position, a second pointer responsive to the downward action of said movable platen, pivotal means carried by one of said pointers, a fixed means carried by the other of said pointers, said pivotal and fixed means being adapted to contact one another upon said mov-

able and second pointers reaching a predetermined relationship, means actuated by said pivotal means for deenergizing said solenoid operating said valve and thereby causing an interruption in the downward action of said movable platen, and means energized upon a downward action of said movable platen arranged to return said second pointer to normal position upon a raising action of said movable platen.

4. In a pressure stroke control of a hydraulic power press, the combination of, a stationary dial, a shaft extending through said stationary dial, a manually movable pointer disposed on one side of said dial and journaled to said shaft, a second pointer disposed on the opposite side of said dial and fixed with respect to said shaft, means actuated by a downward action of a movable platen of said press for rotating said shaft in one direction, means energized by said downward action of said movable platen for rotating said shaft in an opposite direction upon an upward action of said movable platen, and means associated with said pointers adapted to contact one another for causing a release in fluid pressure causing the downward action of said movable platen.

5. In a hydraulic power press having a fluid operated movable platen, the combination of, a solenoid operated valve, a pointer arranged to be fixed at a predetermined position, a second pointer responsive to the downward action of a movable platen, means carried by one of said pointers, means carried by the other of said pointers, said pointer carried means being adapted to contact one another upon said pointers reaching a predetermined relationship, and means actuated by said first named means for deenergizing said solenoid operating said valve and thereby causing an interruption in the downward action of said movable platen.

6. In a hydraulic power press having a fluid operated movable platen, the combination of, a solenoid operated valve, a pointer arranged to be fixed at a predetermined position, a second pointer responsive to a downward action of said movable platen, and means carried by both of said pointers and adapted to contact one another upon said pointers reaching a predetermined relationship to result in the deenergizing of said solenoid operating said valve and cause an interruption in the downward action of said movable platen.

HARRY P. L. LAUSSUCQ.
